UNITED STATES PATENT OFFICE.

LAURA E. ALEXANDER, OF INDIANAPOLIS, INDIANA.

DESIGN FOR A DOLL.

58,863.

Specification for Design.

Patented Sept. 6, 1921.

Application filed November 17, 1920. Serial No. 424,796. Term of patent 7 years.

To all whom it may concern:

Be it known that I, LAURA E. ALEXANDER, a citizen of the United States, residing at Indianapolis, in the county of Marion and State of Indiana, have invented a new and original and ornamental Design for a Doll, of which the following is a specification, reference being had to the accompanying drawing, forming part thereof.

I claim:

The ornamental design for a doll as shown.

LAURA E. ALEXANDER.
